(57) **CLAIM**

The ornamental design for a confectionery product, as shown and described.

DESCRIPTION

1. Confectionery product

FIG. 1.1 is a front perspective view of a confectionery product showing the design;

FIG. 1.2 is a top view thereof;

FIG. 1.3 is a bottom view thereof;

FIG. 1.4 is a front view thereof;

FIG. 1.5 is a rear view thereof;

FIG. 1.6 is a right view thereof;

FIG. 1.7 is a left view thereof.

The figures show the body of the confectionery product without any packaging; the surface shadings are for illustrative purposes only, and form no part of the claimed design.
